(57) **CLAIM**

The ornamental design for a modular aspirated smoke, gas and air quality monitoring system device, as shown and described.

DESCRIPTION

FIG. 1 is a perspective view of the modular aspirated smoke, gas and air quality monitoring system device.

FIG. 2 is a front view thereof.

FIG. 3 is a back view thereof.

FIG. 4 is a top view thereof.

FIG. 5 is a bottom view thereof.

FIG. 6 is a left side view thereof.

FIG. 7 is a right side view thereof; and,

FIG. 8 is a front view of an alternative configuration of use of modular aspirated smoke, gas, and air quality monitoring system device.

The broken lines in the drawings depict unclaimed portions of the article and form no part of the claimed design. The rear view of the article is not disclosed in the drawings and forms no part of the claimed design.
